MECHANICAL MOVEMENT

Filed June 21, 1924

UNITED STATES PATENT OFFICE

MORRIS P. HOLMES, OF CLAREMONT, NEW HAMPSHIRE, ASSIGNOR TO SULLIVAN MANUFACTURING COMPANY, A CORPORATION OF MASSACHUSETTS

MECHANICAL MOVEMENT

Application filed June 21, 1924. Serial No. 721,603.

My invention relates to hoisting mechanisms.

An object of my invention is to provide an improved hoisting mechanism. Another object of my invention is to provide an improved hoisting mechanism having improved driving means therefor. A further object of my invention is to provide an improved hoisting mechanism having improved transmission means between the driving motor and the drum. A still further object of my invention is to provide an improved hoisting mechanism having improved ratchet and pawl reduction mechanism between the driving motor and the drum. These and other objects and advantages of my invention will, however, hereinafter more fully appear.

In the accompanying drawings I have shown for purposes of illustration one form 20 which my invention may assume in practice.

In these drawings,—

Fig. 1 is a central longitudinal vertical sectional view, partially in elevation, of the hoisting mechanism in which my improved 25 transmission mechanism is incorporated.

Fig. 2 is a transverse vertical sectional view taken substantially on line 2—2 of Fig. 1, parts being omitted to facilitate illustration.

Fig. 3 is a detail view of a portion of my 30 improved transmission mechanism.

In this illustrative form of my invention, I have shown a frame 1 provided with standards 2 and 3 on which stub shafts 4 and 5 are suitably journaled, the latter being journaled 35 in bearings 6. The shafts 4 and 5 are formed integral with head members 7 and 8 suitably secured as by bolts to a drum 9, the shaft 5 being connected to the member 8 by means of radially spaced arms, as illustrated. The 40 drum 9 is provided with bores 10 and 11 the ends of which are closed by the head members 7 and 8 and in which a pressure fluid actuated motor, generally designated 12, is disposed which may be of any suitable type but which 45 herein comprises a pair of intermeshing helical tooth rotors 13 and 14 rotating in parallel relation. The motor 12 is adapted to drive the drum 9 through a transmission mechanism of improved form.

50 In my improved construction it will be ob-

served that the rotors 13 and 14 are provided with parallel longitudinally extending shafts 15 and 16 which are provided with eccentric members or cranks 17 and 18 adapted to be driven in opposite relation. The head member 8 is also provided with projecting bosses or lugs 19 and 20 which are provided with slots or grooves 21 and 22 adapted to guide rollers 23 and 24 which are rotatably connected at 25 to pawl members 26 and 27 which are adapted to be urged into operative engagement with ratchet teeth 28 by means of spring pressed plungers 29 slidably mounted in suitable bores 29' formed in the bosses 19 and 20. It will also be observed that these ratchet teeth 28 are formed in the inner periphery of an annular reaction controlling member 30 provided with a projecting annular portion 30' suitably journaled, as at 31, on the arm 3 and provided with an annular external grooved portion 32 in which a suitable brake band 33 is disposed. The brake band 33 is provided with suitable applying mechanism 34. It will moreover be noted that herein the brake band 33 is adapted to frictionally engage the surface of the groove 32 thus preventing rotation of the member 30 as desired. The pawls 26 and 27 are each adapted to be reciprocated by means of a pair of toggle links 35 and 36, the latter being pivoted at 37 on the head member 8 which is secured to the drum 9, as hereinbefore described. The pairs of toggle links 35 and 36 are each connected at the mid pivot 38 to pairs of toggle links 39, 40, 41 and 42, the links 39 and 42 being pivoted at their ends, as at 43 and 44, to the head member 8. The toggle links 39 and 40 are connected at the mid pivot 45 to the connecting link or rod 46 pivoted at 47 on the eccentric member 18, while the links 41 and 42 are connected at the mid pivot 48 to the connecting link or rod 49 pivoted at 50 on eccentric member 17. The drum 9 is provided with annular external flanges 51 and 52, the latter being provided with an annular groove 53 with which a brake band 54 is adapted to cooperate. A flexible cable 55 is adapted to be wound on, or unwound from the drum 9 and guided onto the drum by the flanges 51 and 52.

In the operation of my improved hoisting mechanism fluid pressure is admitted, from any suitable source of supply, to the motor 12, thereby causing the shafts 15 and 16, and consequently eccentric members 17 and 18, to rotate in opposite directions, causing the pawls 26 and 27 to be reciprocated in opposite directions through the pairs of toggle mechanisms 35 and 36, and 39, 40 and 41, 42, respectively, which are driven by means of the connecting links or rods 46 and 49 pivoted on the eccentric members 17 and 18. The brake band 33 is then applied causing the reaction member 30, in which the ratchet teeth 28 are formed, to be held stationary and the brake band 54 is released permitting free rotation of the drum 9. The pawls 26 and 27 then react on the stationary ratchet teeth 28, causing the drum to be rotated at a reduced speed from the rotors 13 and 14 and consequently winding in the cable 55.

As a result of my improvement it will be noted that I have provided a powerful transmission mechanism of exceedingly simple and compact form which greatly reduces the overall length and weight of the hoisting mechanism and which may be applied to a hoisting mechanism of standard form with a minimum of change. It will also be observed that by means of my improved ratchet and pawl reduction mechanism the use of expensive spur tooth reduction gearing is entirely eliminated and that a flexible control of the hoisting mechanism is obtained by means of the brake band and the reaction controlling member.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a power transmission mechanism, a rotatably supported member and means for rotating the same comprising a normally stationary reaction member, driving elements coacting with said stationary member, and means carried by said rotatably supported member for intermittently actuating said driving elements comprising a separate eccentric member and connections actuated thereby for actuating each driving element, said eccentric members being arranged on axes offset from the axis of revolution of said rotatably supported member.

2. A power transmission mechanism comprising a pair of members one of which is rotatable relative to the other, and means for producing said relative rotation comprising driving elements coacting with one of said members and supported by the other member,

and means for actuating said driving elements comprising toggle links, eccentric members operatively connected to the mid pivots of said toggles for actuating said links, and means for driving said eccentric members. 70

3. A power transmission mechanism comprising a pair of members one of which is rotatable relative to the other, and means for producing said relative rotation comprising 75 reciprocable driving elements coacting with one of said members and supported and guided by the other member, and means for reciprocating said driving elements comprising toggle links, eccentric members operatively connected to the mid pivots of said toggles for actuating said links, and means for driving said eccentric members. 80

4. A power transmission mechanism comprising a pair of members one of which is 85 rotatable relative to the other, and means for producing said relative rotation comprising driving elements coacting with one of said members and supported by the other member, and means for actuating said driving elements comprising toggle links, eccentric members for actuating said links, and means carried by said relatively rotatable member for driving said eccentric members. 90

5. A power transmission mechanism comprising relatively movable members one of which is a frictionally controlled reaction member, driving elements coacting with said reaction member and supported and guided by the other member for causing said relative 95 movement, and means for actuating said driving elements comprising toggle links, eccentric members for actuating said links, and means for driving said eccentric members. 100

6. A power transmission mechanism comprising a pair of members one of which is rotatable relative to the other and the other of which is normally stationary, and means for producing said relative rotation comprising 105 driving elements coacting with one of said members and supported by the other member, and means for actuating said driving elements comprising pivotally connected toggle links certain of which are operatively connected to said driving elements, eccentric members operatively connected to the mid pivots of said toggles for actuating said links, and means for driving said eccentric members. 110

7. A power transmission mechanism comprising a pair of members one of which is rotatable relative to the other and the other of which is normally stationary, and means for producing said relative rotation comprising 115 a driving element coacting with one of said members and supported by the other member, and means for actuating said driving element comprising pivotally connected links, certain of which are operatively connected to said driving element, an eccentric 120

125

130

member for actuating said links, and means carried by said rotatable member for driving said eccentric member.

8. A power transmission mechanism comprising a rotatably supported member and means for rotating the same comprising a stationary member, a driving element coacting with said stationary member and supported by said rotatable member, and means for actuating said driving element comprising pivotally connected toggle links operatively connected to said element, an eccentric member operatively connected to the mid pivot of said toggle for actuating said links, and means for driving said eccentric member.

9. A power transmission mechanism comprising a rotatably supported member and means for rotating the same comprising a stationary member, a driving element coacting with said stationary member and supported by said rotatable member, and means for actuating said driving element comprising pivotally connected toggle links operatively connected to said element, an eccentric member for actuating said links, and means carried by said rotatable member for driving said eccentric member.

10. A power transmission mechanism comprising a rotatably supported member and means for rotating the same comprising a stationary member, reciprocable driving elements coacting with said stationary member and supported and guided by said rotatable member, and means carried by said rotatably supported member for actuating said driving elements including pivotally connected toggle links operatively connected to said driving elements, a plurality of eccentric members connected to said links for actuating said links and arranged on axes offset from the axis of revolution of said rotatably supported member, and means for driving said eccentric members.

45 11. A power transmission mechanism comprising a rotatably supported member and means for rotating the same comprising a stationary member, reciprocable driving elements coacting with said stationary member and supported and guided by said rotatable member, and means for actuating said driving elements comprising pivotally connected toggle links operatively connected to said driving elements, a plurality of eccentric members for actuating said links, and means carried by said rotatable member for driving said eccentric members.

50 12. A power transmission mechanism comprising a stationary reaction member, a movable member, a driving element coacting with said stationary member and supported by said movable member for causing relative movement between said members, and means for actuating said driving element comprising a pair of pivotally connected links one

having an end operatively connected to said driving element and the other having an end pivoted on said movable member on which said driving element is supported, a second pair of toggle links pivotally connected to said first pair of links, an eccentric member connected to said second pair of links for actuating all of said links, and means carried by said movable member for driving said eccentric member.

70 13. A power transmission mechanism comprising relatively rotatable members, driving elements coacting with one of said members and supported by the other, and means for actuating said driving elements comprising toggle levers operatively connected to said driving elements, eccentric members operatively connected to the mid pivots of said toggles for actuating said levers, and means for driving said eccentric members.

75 14. A power transmission mechanism comprising relatively rotatable members, driving elements coacting with one of said members and supported by the other, and means for actuating said driving elements comprising toggle levers operatively connected to said driving elements, eccentric members for actuating said levers, and means carried by said rotatable member for driving said eccentric members.

80 15. A power transmission mechanism comprising a stationary member, a rotatable member, reciprocable driving elements coacting with said stationary member and supported and guided by said rotatable member, and means for actuating said driving elements comprising toggle levers operatively connected to said elements, a plurality of eccentric members carried by said rotatable member and rotatable on parallel axes which move in an orbit about the axis of said rotatable member, and means for driving said eccentric members.

85 16. A power transmission mechanism comprising a stationary member and a rotatable member, reciprocable driving elements coacting with said stationary member and supported and guided by said rotatable member, and means for actuating said driving elements comprising toggle levers operatively connected to said elements, a plurality of eccentric members carried by said rotatable member and rotatable on parallel axes which move in an orbit about the axis of said rotatable member, and means carried by said rotatable member for driving said eccentric members.

90 17. A power transmission mechanism comprising a stationary member, a rotatable member, driving elements comprising reciprocable spring pressed pawls coacting with said stationary member and supported and guided by said rotatable member, and means for actuating said driving elements comprising pairs of toggle links movable in parallel

planes and operatively connected to said driving elements and having ends pivotally connected to said rotatable member, eccentric members rotatable on parallel axes for actuating said links, and means carried by said rotatable member for driving said eccentric members.

18. A power transmission mechanism comprising relatively movable members one of which is a stationary reaction member having ratchet teeth formed thereon, driving elements alternately coacting with one of said members and supported by the other member for causing said relative movement, and means for actuating said driving element comprising toggle links operatively connected to said driving elements, eccentric members rotatable in opposite directions for actuating said links, and means for driving said eccentric members.

19. A power transmission mechanism comprising a stationary member and a rotatable member, reciprocable driving elements coacting with said stationary member and supported and guided by said rotatable member, and means for actuating said driving elements comprising pairs of pivotally connected toggle links, a link of each pair having one end operatively connected to a driving element and the other link of the pair having an end connected to said movable member, second pairs of links, certain links of said second pairs having ends operatively connected to said first pairs of links and other links of said second pairs having ends connected to said movable member, a plurality of eccentric members, links connecting said eccentric members respectively with said second pairs of links for actuating all of said links, and means carried by said rotatable member for driving said eccentric members.

In testimony whereof I affix my signature.
MORRIS P. HOLMES.
